(57) **CLAIM**

The ornamental design for a lab coat with mandarin collar and flared skirt as shown and described.

DESCRIPTION

FIG. 1 is a perspective view of a lab coat with mandarin collar and flared skirt showing my new design;

FIG. 2 is a front elevational view thereof;

FIG. 3 is a front elevational view thereof in an open configuration;

FIG. 4 is a rear elevation view thereof in an open configuration;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a rear elevational view thereof.

The broken lines in the figures show portions of the design which form no part of the claim. The additional broken lines showing a face and hands in FIG. 2 depict environment which forms no part of the claimed design.

The cross-hatch shading is fragmentarily shown for convenience of illustration; it being understood that the cross-hatch shading is uniformly continued over the surface on which it appears.
